Primary Examiner — Marie D. Fast Horse*(74) Attorney, Agent, or Firm* — Ziegler IP Law Group, LLC(57) **CLAIM**

The ornamental design for a portable wireless hub, as shown and described.

DESCRIPTION

FIG. 1 is a top, back side perspective view for a portable wireless hub;

FIG. 2 is a back perspective view thereof shown larger for clarity;

FIG. 3 is a top view thereof shown larger for clarity;

FIG. 4 is a top, front side perspective thereof;

FIG. 5 is a back view thereof; and,

FIG. 6 is a side view thereof.

The broken dashed lines in the figures depicts a part of the portable wireless hub that forms no part of the claimed design, while all other broken lines consisting of uneven dashed lines define the boundary of the claim which extends to the boundary but does not include the boundary. All broken lines form no part of the claim.

1 Claim, 6 Drawing Sheets(56)
